UNITED STATES PATENT OFFICE.

DAN LA COUR, OF CHARLOTTENLUND, NEAR COPENHAGEN, AND CECIL VILHELM SCHOU, OF COPENHAGEN, DENMARK.

VAPORIZING-STARTER.

1,249,425.

Specification of Letters Patent. Patented Dec. 11, 1917.

Application filed June 20, 1916. Serial No. 104,790.

To all whom it may concern:

Be it known that we, DAN LA COUR and CECIL VILHELM SCHOU, subjects of the King of Denmark, residing at Charlottenlund, 5 near Copenhagen, Denmark, and Copenhagen, Denmark, respectively, have invented new and useful Vaporizing-Starters; and we do hereby declare the following to be a full, clear, and exact description of the same.

10 The invention relates to an apparatus for speedily causing liquid fuel such as kerosene, fuel oil, etc., to evaporize, and especially aims at a speedy and convenient starting of combustion engines which work with 15 such fuel, and at igniting such burners which demand a previous heating, which when effected by means of a flame, takes a comparatively long time and is sometimes made impossible for instance on account of 20 wind when such lamps are used in the free air.

Such an apparatus consists generally in 25 a member of well conducting metal such as copper, which is adapted for accommodating a heating cartridge, which through chemical reaction between the substances of which it consists is able to develop a considerable quantity of heat in a small space, and which is shaped in such a manner that it conducts 30 the heat to the place where it is to be utilized for evaporizing of the liquid fuel in question.

Different modifications of the invention are shown in the drawing, where—

5 Figure 1 shows a longitudinal section of the apparatus adapted for being arranged on a combustion engine,

Fig. 2 a different modification and

Fig. 3 a modification of the apparatus for 10 use in speedy starting of an ordinary kerosene-soldering-lamp.

In Fig. 1 *a* designates a copper member having a free outer surface *b* and a free surface *c* found in the combustion chamber of 15 the engine. The member *a* is by means of the ring *d* in a suitable manner secured on the combustion chamber, which depending on the circumstances may be closed by the cylinder cover or may consist of a so-called 20 glow-head. The packings *f* which consist of asbestos or the like, at one time effect tightness and heat insulating. The injection nozzle *g* is directed toward the free surface. When the motor is to be started, a heat

cartridge *h* is put on the surface *b* and ignited, whereupon an insulating cover *k* is put over, and in the course of a few seconds the member *a* will become so hot that the motor can be started and work.

The use of copper for the member *a* is of 60 importance, because the quantity of heat given off by the same, will, owing to the liquid fuel being injected against a comparatively small surface, practically instantaneously be substituted by admission of heat 65 from the neighboring parts of the said member. A member of iron would not, or but badly, be employable.

If a cartridge containing aluminium powder and iron oxid be used, it is appropriate 70 to protect the insulating cover *k* by means of a copper plate *m*.

Fig. 2 shows a similar modification, meant for being introduced from the side; but otherwise acting in a manner quite similar to 75 that shown in Fig. 1.

Fig. 3 shows one of the ordinary evaporizing burners for kerosene, in which the evaporizing of the kerosene introduced through the pipe *n* under pressure is effected by the heat from the flame proper. Such a burner must, in order to ignite the fuel, be heated to a temperature above the boiling point of the kerosene, and this is according to the present invention effected by some 85 part of the tube through which the kerosene is introduced and in which the evaporizing is to take place arranging a copper member *o* which can accommodate a heat cartridge and transmit the heat to the tube.

In a similar manner the apparatus can be 90 used for starting the well known kerosene incandescent light burners.

Having thus fully described our invention, we claim as new and desire to secure by Letters Patent:

1. Device for speedily evaporizing liquid fuel in a closed space comprising a member of a well conducting metal having a concave outer surface adapted to hold and be heated 100 by a heating cartridge the said member being adapted to convey the heat to a place in the said closed space where the evaporizing is to be effected.

2. Device for speedily evaporizing liquid 105 fuel in a closed space comprising a member of a well conducting metal having a concave outer surface adapted to hold and be heated

by a heating cartridge the said member passing through an opening in the wall of the said closed space.

3. Device for speedily evaporizing liquid fuel in a closed space comprising a member of a well conducting metal having a concave outer surface adapted to hold and be heated by a heating cartridge the said member passing through an opening in the wall of the

said closed space and means for insulating the said member from the said wall.

In testimony whereof, we affixed our signatures in presence of two witnesses.

DAN LA COUR.

CECIL VILHELM SCHOU.
